UNITED STATES PATENT OFFICE

2,430,338

SHOE

Salomon Heiman, New York, N. Y.

Application February 14, 1946, Serial No. 647,579

3 Claims. (Cl. 36—12)

1

The present invention relates to footwear, particularly ladies' shoes and slippers and has for its main object to provide a method and means for joining the shoe upper, platform and sole in the quickest possible way and simultaneously, thereby saving labor and materials.

To accomplish this, my method consists in that two complementary zipper strips of any suitable construction are stitched or otherwise permanently attached, one to and all around the shoe upper and its heel and the other to and all around the sole, then causing the interlocking of the zipper teeth by the usual slide, then permanently fixing the end portion of said zipper teeth to the shoe.

My invention will be readily understood by reference to the accompanying drawing which constitutes part of this specification and in which similar reference characters denote corresponding parts.

Fig. 1 is a side elevation of a ladies' shoe constructed according to my invention.

Fig. 2 is a rear end elevation thereof.

Fig. 3 is a cross section on line 3—3 of Fig. 1 and

Fig. 4 is a somewhat enlarged elevation of a part of a zipper whose slide has been removed and whose complementary zipper elements or teeth are shown permanently fixed in interengaging position.

In the drawing, 10 denotes the shoe upper of a lady's shoe made of any shape and material, 11 denotes the shoe sole, 12 the heel and 13 the platform which as usual may consist of layers of felt, cork or the like. Stitched to the bottom downwardly folded edges 10a of the shoe upper and of its heel portion is the cloth strip 14 carrying a row of ordinary zipper elements or teeth 15 and stitched to the upwardly folded edges 16a of the outer leather covering 16 of the sole 11 is the cloth strip 14a carrying the complementary row of zipper teeth 15a. These two strips, 14, 14a are arranged with their teeth or zipper elements 15, 15a contiguous and parallel to one another and extend all around the circumference of the shoe. After effecting the engagement of the complementary zipper teeth 15, 15a with one another by the usual manipulation of the zipper slide (not shown) the latter may be removed and the end teeth or zipper elements 15, 15a are fixed in position by suitable means, such as staples 17 or the like.

A plate 18 of metal or other suitable material may be used to shield the fixed ends of the zipper strips, and may be fixed in position by nails 19 or the like.

The zipper teeth may be advantageously made

of shiny metal, so as to, at the same time, serve as an ornament.

It is obvious that other means may be used to permanently fix the interengaging zipper teeth in locked position, and the attachment of the cloth strips 14, 14a to the parts of the shoe for the purpose described may also be varied without departing from the principle of my invention. I, therefore, do not wish to restrict myself to the details described and shown.

What I claim is:

1. In shoe manufacturing, the method of permanently joining the shoe upper, platform and sole, consisting in attaching to and all around the bottom edges of the shoe upper and its heel portion one of the two complementary ordinary zipper strips, and the other to, and all around the edges of the sole, effecting the interlocking of said complementary zipper strips by the zipper slide removing said slide from the ends of the interlocked zipper strips, and permanently fixing said ends of the zipper strips to the shoe in locked position.
2. In a shoe, the combination with its shoe upper, platform and sole, of a zipper, one strip of which is permanently attached to and all around the bottom edge of the shoe upper and of its heel portion and the other of which is permanently attached to and all around the edge of the sole, a slide for interlocking of said zipper strips with one another said slide being removed from said strips after they have been interlocked, and means for permanently fixing the ends of said zipper strips to the shoe in interlocked condition.
3. In a shoe, the combination with its shoe upper, platform and sole, of a zipper, one strip of which is permanently attached to and all around the bottom edge of the shoe upper and of its heel portion and the other of which is permanently attached to and all around the edge of the sole, a slide for the interlocking of said zipper strip with one another, said slide being removed from the said zipper strips after they have been interlocked, means for permanently fixing the ends of the zipper strips to the shoe in interlocked position and a shield mounted over the fixed ends of the zipper strips.

SALOMON HEIMAN.
